FLAW DETECTOR MECHANISM

Harcourt C. Drake, Hempstead, N. Y., assignor
to Sperry Products, Inc., Brooklyn, N. Y., a
corporation of New York

Application November 17, 1933, Serial No. 698,399

4 Claims. (Cl. 177—311)

This invention relates to rail flaw detector mechanism of the type employed in the Sperry rail flaw detector cars. The principle of operation employed in said cars is now well known and consists in passing current through the rail to establish an electromagnetic field surrounding the same and exploring this field for irregularities due to the presence of internal flaws by means of induction coils designed to induce an E. M. F. whenever an irregularity in the electromagnetic field is encountered.

The present invention has for its principal object the provision of means whereby an operator can at all times know whether the detector mechanism is functioning.

Further objects and advantages of my invention will become apparent in the following detailed description thereof.

In the accompanying drawing, Fig. 1 is a side elevation of a portion of a Sperry rail flaw detector car.

Fig. 2 is a wiring diagram embodying my invention.

Referring to the drawing, there is disclosed a portion of a Sperry rail flaw detector car comprising the car body 10 within which is mounted a generator G adapted to supply current to the rail to establish an electromagnetic field surrounding the same. The current from generator G may be passed into and out of the rail by means of sets of brushes 11 and 12 carried by a current brush carriage 15, said carriage being supported from the car body 10 by means such as cables 16 and springs, not shown, which normally maintain the current brush carriage in raised or ineffective position. When it is desired to lower such carriage into engagement with the rail, fluid pressure, such as compressed air, is supplied to cylinders 17 to depress pistons 18 operating therein, said pistons being connected to the current brush carriage so that said carriage is lowered against the action of the retractile springs. The current brush carriage may be adapted to ride along the rail on means such as flanged wheels 19.

The electromagnetic field surrounding the rail is uniform as long as there are no flaws. When flaws occur there is a distortion of the electromagnetic field in the region of the flaw and such distortions are designed to be detected by induction means which in the present case comprise a pair of opposed induction coils 20 supported in a housing 21, carried by a detector carriage 22 which is designed to be supported on the current brush carriage for movement independent thereof by means such as loose-fitting bolts 23

and springs 24 constituting limited universal joints. The detector carriage 22 may be supported on the rail surface by means such as rollers 25. It will now be seen that as the car travels along the rail R the inductive means 20 are maintained a constant distance above the rail surface and will normally cut a constant number of lines of force. When a region of flaw is encountered one of the coils will cut a different number of lines of force and there will be generated a differential E. M. F. which after being amplified by an amplifier A may be caused to operate indicating means such as pens operating on a moving chart.

The output of amplifier A is caused to energize a plurality of relays 30, 31 of varying degrees of strength so that a region of weak flaw will energize, for example, only relay 30, while a region of considerable flaw will energize relays 30 and 31. The energization of said relays is caused to operate pens P and P', respectively, by attracting armatures 30' and 31' to close contacts 32 and 33 which will energize pen magnets 34 and 35 to attract the pens P, P'. Said pens normally trace straight lines along a moving chart but when the magnets 34, 35 are energized the pens are attracted out of their normal path to make a jog in the line and thus indicate the presence of a flaw.

Since every rail joint will distort the electromagnetic field to a very marked degree, the detector mechanism hereinbefore described would pick up every rail joint and cause the pens P and P' to be actuated several times in passing over each rail joint to give an indication as of a prolonged region of flaw. This is due to the fact that at each joint there are angle bars of considerable length, bolts, etc., all of which tend to distort the normal axis of the current. There is therefore provided means for cutting out the indications of pens P and P' when a joint is reached. For this purpose, there are provided joint fingers 40 and 41 in advance of the detector mechanism and to the rear of it. These joint fingers are adapted to engage the side of the rail head so that they will engage the projecting part of the angle bar when a joint is reached, and they are so positioned that the rear finger will engage the angle bar before the forward finger has passed beyond it. Therefore, one or the other of fingers 40, 41 will be in engagement with said angle bar throughout the entire period that the detector mechanism 20 is passing over said angle bar. The engagement of joint fingers 40, 41 with the angle bar is caused to break the circuit to the pen relays 34, 35 by reason of the 55

fact that said fingers are pivoted at 40', 41' and have means beyond said pivot for closing contacts 42, 43 which are arranged in parallel so that closing of either set of contacts 42, 43 will energize a relay 45 to attract an armature 46 and break contacts 47 which are in the circuit leading from output relays 30 and 31 to the pen relays 34 and 35. Thus, although relays 30 and 31 are energized by reason of the detector coils 5 passing over the joint, the pens P and P' are not actuated.

At the same time that relay 45 is energized a relay 48 is also energized by the closing of contacts 42 or 43, to attract an armature 49 and close the set of contacts 50 to energize a joint pen relay 51 designed to operate a joint pen J. Said pen also traces a straight line normally on the chart, but when relay 51 is energized by the joint cutout fingers 40 and 41 the pen is attracted 10 to make a jog in the line and thus indicate the presence of a flaw. As soon as the joint is passed over, that is, as soon as the rear joint cutout finger 41 has passed beyond the angle bar, relays 45 and 48 are de-energized to close contacts 47 15 and thus render pen magnets 34 and 35 again effective to respond to impulses transmitted thereto by output relays 30 and 31 and thus permit pens P and P' to operate again. At the same time contacts 50 open and the joint pen J is returned to its normal indicating position.

It may occur that for some reason, such as broken connections, short circuits and the like, the detector system originating with the induction coils 28 and extending by means of electrical connections into the amplifier and thence to the output relays 30 and 31, may be inoperative and may not be functioning. It is very difficult to detect such a condition ordinarily because the pens P and P' function only when a flaw comes through, and if the detector system has broken down, pens P and P' will simply make a straight line record showing no flaws and the operator will merely consider that the track traversed is without internal fissures, whereas in fact 40 the detector system is not functioning at all. In order to have some indication as to whether or not the detector system is functioning I utilize that interval during which the pen relays 34 and 35 are actuated by the joint cutout mechanism described above. That is to say, when the contacts 47 are opened to break the pen relay circuits 34, 35, I provide means for operating a circuit from the output of the amplifier and place within that circuit some suitable signal.

In order to accomplish the above object, I provide in the output of the amplifier an additional output relay 29 of lesser strength than either relay 30 or 31 so that any output which would be sufficient to actuate the output relays 30 and 31 55 and hence the relay pens 34 and 35 will be sufficient to energize relay 29. I cause said relay 29 when energized to attract an armature 29' to close contacts 60 which will close a circuit in parallel with joint pen relay 51 (since the 60 joint pen relay circuit is operative during this interval), in which circuit I place a suitable signal 61 which may be a light, as shown or a sound signal or any other suitable indicator. The shunt circuit begins at points 62 and 63 and includes 65 the leads 64, 65. The effect of this construction is that when contacts 50 are closed by the joint cutout mechanism hereinbefore described to close the circuit through joint pen relay 51, relay 29 is energized by the output of amplifier A to 70 close the shunt circuit by closing contacts 60 and 75

thus actuate the indicator 61. Relay 29 will be energized when the detector mechanism passes over the rail joint for the reason described above, namely, that the rail joint distorts the magnetic field for a considerable distance and such distortion is picked up by the detector coils 28, is amplified by amplifier A and therefore energizes one or more of the output relays 29, 30, 31. The relays 30 and 31 do not energize pen relays 34 and 35 when the mechanism passes over the rail joint because the circuit through relays 34 and 35 is broken at 47, but the relay 29 does close the shunt circuit through the indicator 61 if the detector mechanism is operated. Should there be some fault in the detector mechanism anywhere between the induction coils 28 and the output relays 29, 30 and 31 it will at once become apparent because of the failure of signal 61 to be operated when the joint pen indicates that the mechanism is passing over a joint.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. In a rail flaw detector mechanism, means responsive to flaws, a plurality of indicating means, means whereby said indicating means are actuated by said responsive means, means whereby one of said indicating means is normally conditioned to be operated and the other of said indicating means is normally conditioned not to be operated, means actuated by the rail joint, a rail joint indicator, means whereby said rail joint indicator is actuated by said rail-joint-actuated means, means whereby said rail-joint-actuated means conditions said first indicating means not to be operated when said responsive means passes over a rail joint, and means whereby said second indicating means is conditioned to be operated when said rail joint indicator is actuated.

2. In a rail flaw detector mechanism, means responsive to flaws, electrically operated indicating means, means whereby said indicating means is actuated by said responsive means, means actuated by the rail joint, a second electrically operated indicating means, means whereby said second indicating means is actuated by said rail-joint-actuated means, an auxiliary electrically operated indicating means adapted to be conditioned to be operated and conditioned not to be operated, means whereby said auxiliary indicating means is actuated by said responsive means, means whereby said rail-joint-actuated means conditions said first indicating means not to be operated when said responsive means passes over a rail joint, and means whereby said auxiliary indicating means is conditioned to be operated and conditioned not to be operated when said second indicating means is conditioned to be operated and conditioned not to be operated.

3. In a rail flaw detector mechanism, means responsive to flaws, a plurality of electromagnetic relays actuated by said responsive means, a plu-

- 5 rality of indicating circuits, means whereby said circuits are controlled by said respective relays, means for normally maintaining one of said circuits in condition to be operated and the other of said circuits in condition not to be operated, and means whereby said first circuit is conditioned not to be operated and said second circuit is conditioned to be operated when said responsive means passes over a rail joint.
- 10 4. In a rail flaw detector mechanism, means responsive to flaws, a plurality of electromagnetic relays responsive to currents of varying magnitudes actuated by said responsive means,
- a plurality of indicating circuits, means whereby the relay responsive to relatively larger currents controls one of said circuits and the relay responsive to relatively smaller currents controls the other of said circuits, means for normally maintaining said first circuit in condition to be operated and said second circuit in condition not to be operated, and means whereby said first circuit is conditioned not to be operated and said second circuit conditioned to be operated when said responsive means passes over a rail joint.
